H. L. CRAFTS

AUTOMOBILE RADIATOR CONDENSER

Filed April 15, 1921

FIG. 1

FIG. 2

FIG. 3

INVENTOR
Harold L. Crafts
BY
Davis & Simms
his ATTORNEYS

UNITED STATES PATENT OFFICE.

HAROLD L. CRAFTS, OF ROCHESTER, NEW YORK.

AUTOMOBILE RADIATOR CONDENSER.

Application filed April 15, 1921. Serial No. 461,731.

To all whom it may concern:

Be it known that I, HAROLD L. CRAFTS, a citizen of the United States, and resident of Rochester, in the county of Monroe and State of New York, have invented certain new and useful Improvements in Automobile Radiator Condensers, of which the following is a specification.

The present invention relates to automobile radiator condensers, and an object thereof is to provide an inexpensive compact structure which may be readily fitted to the filling tube of a radiator for the purpose of condensing the vapors arising therefrom and for returning the condensed liquid to the radiator. Another object of the invention is to provide a compact construction which may be formed by a metal casting and will have a maximum heat dissipating surface 20 with a maximum condensing chamber.

To these and other ends the invention consists of certain parts and combinations of parts, all of which will be hereinafter described, the novel features being pointed out 25 in the appended claims.

In the drawings:

Fig. 1 shows in elevation, a condenser constructed in accordance with this invention;

Fig. 2 is an axial section through the condenser showing the manner in which it is connected to the filling tube of a radiator; and

Fig. 3 is a plan view of the condenser.

Referring more particularly to the drawings, 1 indicates the filling tube of a radiator and 2 the cap or closure which is externally threaded and engages with internal threads on the filling tube. This cap or closure

is surmounted by the condenser 3 which is a cast metal body having a depending nipple 4 passed through a central opening in the cap and secured in place by a nut 5 which bears against a washer 6. The cast body 3 may be formed of aluminum or other suitable material and provided with a plurality of annular ribs 7 to increase the surface of the body in order to provide a large heat dissipating surface.

The body is provided with an internal chamber preferably formed in two parts 8 and 9 separated by a partition or wall 10 which at 11 is spaced from the top of the chamber so as to provide communication between the two parts of the chamber. One

of these parts communicates with the opening 12 in the nipple, while the other part is provided with a lateral port or outlet 13 to the atmosphere, preferably between two of the radiating flanges 7 and preferably also inclined upwardly so that condensed matters cannot pass through the opening. The lower portion of the part 9 of the chamber communicates with the part 8 through a seal 14 in which the lower end of the partition 10 depends, one side of the seal opening to the part 9 of the chamber and the other side of the seal opening to the part 8. The walls of the two chambers may be provided with alternately arranged ribs 15 and these ribs, together with the form of the chamber, provide a circuitous passage through which the vapors are caused to travel before reaching the outlet 13. This circuitous passage condenses the vapors which are collected in the seal 14 from which they overflow into the radiator by way of the chamber 8 and the passage 12 in the nipple 4.

From the foregoing it will be seen that there has been provided a condenser in the form of a cast metal body with projecting heat dissipating ribs, said body surmounting a closure for a radiator tube. There has also been provided a cast body with a circuitous passage which returns the condensed liquid to the radiator. The condenser has a seal which makes it possible to provide a circuitous passage in the condenser while returning the condensed liquid to the radiator.

What I claim as my invention and desire to secure by Letters Patent is:

1. A condenser having a condensing chamber provided with an inlet at its bottom, a seal for collecting the condensed matters, said seal communicating with the inlet so that the overflow from the seal flows to the inlet.

2. A condenser having a chamber provided with an inlet at the bottom and having also a partition in the chamber dividing the latter into two parts, communicating at the upper end of the chamber, one of said parts being normally open to the inlet, and a seal at the lower end of the other of said chamber parts communicating with the inlet.

3. A condenser having a chamber provided with an inlet at its bottom and having also a partition in the chamber dividing the latter into two parts, communicating at the

upper end of the chamber, one of said parts being normally open to the inlet, and a seal at the lower end of the other of said chamber parts communicating with the inlet, the 5 condenser being provided with a port in the second part above the seal and below the communication of said second part with the first named part.

4. A condenser comprising a body having 10 a chamber formed therein with an inlet at the bottom of the body, a partition in said chamber dividing the latter into two parts, the upper end of the partition being spaced from the top of the chamber to provide communication between such two parts, a seal 15 into which the lower end of the partition depends, said seal communicating on one side of the partition with one of the parts of the chamber and on the other side of the 20 partition with the other part of the cham-

ber, and one of said parts having open communication with the inlet.

5. A condenser comprising a body having a chamber formed therein with an inlet at the bottom of the body, a partition in said chamber dividing the latter into two parts, the upper end of the partition being spaced from the top of the chamber to provide communication between such two parts, a seal 25 into which the lower end of the partition depends, said seal communicating on one side of the partition with one of the parts of the chamber and on the other side of the partition with the other part of the chamber, one of said chambered parts having open 30 communication with the inlet and the condenser having a port leading from the other of said parts at a point between the upper and the lower edge of the partition. 35

HAROLD L. CRAFTS.
